UNITED STATES PATENT OFFICE.

JAMES CALVERT, OF DONAGHCLONEY, IRELAND, ASSIGNOR TO SIR ROBERT MORRIS LIDDELL, OF DONAGHCLONEY, IRELAND.

GRIPPING DEVICE FOR HOLDING FLAX DURING SCUTCHING OPERATIONS.

1,323,012.

Specification of Letters Patent.

Patented Nov. 25, 1919.

Application filed July 31, 1918. Serial No. 247,590.

To all whom it may concern:

Be it known that I, JAMES CALVERT, a subject of the King of Great Britain and Ireland, of Donaghcloney, in the county of 5 Down, Ireland, mechanic, have invented certain new and useful Improvements in or Relating to Gripping Devices for Holding Flax During Scutching Operations, of which the following is a specification.

10 This invention relates to gripping devices for holding flax during scutching operations. The object of this invention is to provide an improved gripping device.

A gripping device made in accordance 15 with this invention comprises an arm pivoted to a stand or the like, a pair of jaws or the like at the end of the arm, means for rocking the arm to and from the stock, means for opening the jaws when the arm 20 is moved away from the stock, means for closing the jaws when the arm is moved toward the stock, and means for holding the jaws closed while the arm is held in a position in which the flax falls over the edge 25 of the stock.

Referring to the drawings filed herewith:—

Figure 1 is a diagrammatic elevation of one form of gripping device made in accordance with this invention.

Fig. 2 is a diagram showing an alternative construction in the form shown in Fig. 1.

Fig. 3 is a diagram showing the device 35 constructed as shown in Fig. 2, adapted for use with a scutching machine of the usual type.

a is a wooden or iron plate technically known as the stock, behind which are 40 mounted a series of revolving wheels provided with blades adapted to beat the flax held over the edge of the stock in the process of scutching by which the woody shell inclosing the fiber is removed.

45 *b* is an arm pivoted at *c* and provided with a jaw *d*. The arm *b* is provided with a bracket *e* on which is pivoted a lever *f* and a link *g*. To the link *g* is connected a link *h*. The link *h* is connected to the stand *j* 50 by a spring *k*. In front of the stock *a* is disposed a pair of horizontal guides *m* on which are mounted rollers *n* and *o*. *n* is attached to the rear guide and there is a space between *n* and the front guide to 55 admit the free passage of the link *g*, which

passes between the guide bars. The link *h* passes through a bracket *l* attached to the guide *m*. The roller *n* is adapted to form a stop to the lever *f* and the roller *o* is adapted to form a stop to the arm *b*. The 60 roller *i* which connects links *g* and *h* projects behind *g*. This projection rests on the lever *f* and through the influence of the spring *h* helps to force the end of the lever *f* in a downward direction and facilitate the 65 opening of the jaws *s* and *d*. The jaw *d* is provided with an extension *p* on which is mounted stop or roller *q*. The extension *p* forms a guide to the sliding bar *r* which 70 slides on the arm *b*. The sliding bar *r* is provided with a jaw *s* which is adapted to co-act with the jaw *d* on the arm *b*. To the sliding bar *r* are attached a pair of guide plates *t* between which is mounted a roller *v* adapted to form a stop to one end of the 75 lever *f* which passes into the space between the guide plates. The sliding bar is connected to the stand *j* by a link *w* and spring *x*. A handle *y* is mounted on the arm *b* by which the arm is rocked back and forth on 80 the pivot *c*. The jaw *s* is provided with a tongue *z* adapted to co-act with a groove in the jaw *d*.

In operating the scutcher holding the handle *y* moves the arm *b* and sliding bar *r* 85 forward to the position shown in the diagram. As the arm comes forward one end of the lever *f* strikes the stop *n* causing the lever to rock on its pivot and lift the sliding bar *r* so as to raise the jaw *s* away from 90 the jaw *d* against the action of the spring *x*. Flax is placed between the jaws, and the scutcher moves the arm *b* and sliding bar *r* back. The spring *x* closes the jaws and holds them in the closed position. When 95 the arm is back the flax falls over the stock *a* where it is beaten by the blades on the wheels already referred to but not shown. The spring *h* counterbalances the spring *x* and assists the scutcher in moving the arm 100 and sliding bar back. When the operation is complete the scutcher moves the arm *b* and sliding bar *r* forward opening the jaws *s* and *d*, the fiber is then removed and fresh flax is placed in the jaw and the operation 105 repeated.

The alternative construction of this flax gripping device shown in Fig. 2, comprises a frame *j'*, on which is mounted a weighted lever *x'*. Pivoted at *c* on the frame *j'* is a 110

bent arm b provided with the gripping jaw d and handle y attached to its upper end. Pivoted to the bent arm b at b' is a link g' . Slidably mounted upon b is the member r the top end of which forms the upper gripping jaw s while to the lower end is attached the link w' which connects it through the medium of link g' and link h to a weighted lever x' . This weighted lever is so arranged that when the arm b and sliding member r are in the position shown, the weight on end of lever x' rests upon the ground, while if the arm b is moved to the right away from the scutching handles, the jaws d s of the gripper are opened to allow the flax to be removed and changed. When the arm b is moved back toward the scutching handles, the weighted lever x' is raised from the ground so that while the flax is being acted upon by the scutching handles, the weighted lever x' is acting upon the jaws d s through the medium of the link h , lever g , link w' , and sliding member r thus holding the flax firmly against the pull of the handles. If necessary the arm b can be balanced against the pull of the weighted lever x' by means of a spring or weight such as m suitably placed for such purpose, or a suitably placed spring may be substituted for the weighted lever x' .

This flax gripping arrangement may be mounted either directly upon the stock a as shown in Fig. 1 or it may be mounted upon the frame as shown in Fig. 2, which is adapted for attaching the apparatus to the stocks in existing scutch mills.

A gripping device made in accordance with this invention for holding flax during scutching operations does away with the necessity of the scutcher holding the flax in his hand and avoids the risk of injury to the scutcher. The yield of scutched flax is increased by the use of a gripping device made in accordance with this invention, as owing to the rigidity of the grip the blades on the wheel or "handles" as they are known in the trade do not pull the weaker and shorter

fibers of the flax out in the same way in which they are pulled from the scutcher's hands, which is liable to happen at all times, and especially when the scutcher's hands become tired and weaker toward the end of the day.

With the use of a gripping device made in accordance with this invention, unskilled labor may take the place of skilled scutchers.

What I claim and desire to secure by Letters Patent is:—

1. A gripping device arranged and adapted to operate in connection with a scutching machine comprising an arm pivoted to a stand, a pair of jaws at the end of the arm, means for rocking the arm to and from the stand, means for opening the jaws when the arm is moved in one direction, and means for closing the jaws when the arm is moved in the other direction.

2. A gripping device arranged and adapted to operate in connection with a scutching machine comprising a stand, an arm provided with a jaw pivoted to the stand, a sliding bar mounted on said arm, a jaw on said sliding bar and means for moving the sliding bar with respect to the arm as it is rocked on its pivot.

3. A gripping device comprising a stand, an arm provided with a jaw pivoted to the stand, a sliding bar mounted on said arm, a jaw on said sliding bar and means for moving the sliding bar with respect to the arm as it is rocked on its pivot, said means including two springy elements in opposition to one another for holding the jaws closed in the working position of said arm, and for assisting the return of the arm to the working position.

In witness whereof I have hereunto signed my name in the presence of two subscribing witnesses.

JAMES CALVERT.
